DESIGN FOR A FLUORESCENT LIGHTING FIXTURE FOR PASSENGER VEHICLES

Eric B. Hallman, Philadelphia, Pa., assignor to
Electric Service Supplies Company, Philadel-
phia, Pa., a corporation of Pennsylvania

Application March 12, 1942, Serial No. 106,172

Term of patent 14 years

To all whom it may concern:

Be it known that I, Eric B. Hallman, a citizen
of the United States and a resident of Phila-
delphia, county of Philadelphia, State of Pennsyl-
vania, have invented a new, original, and ornamental
Design for a Fluorescent Lighting Fixture
for Passenger Vehicles, of which the following is
a specification, reference being had to the accom-
panying drawing, forming a part thereof,
wherein:

Figure 1 is a perspective view of a fluorescent
lighting fixture for passenger vehicles, showing
my new design;

Figure 2 is a bottom plan view thereof;
Figure 3 is a side elevational view thereof;
Figure 4 is an enlarged perspective view of the
central part of the fixture; and

Figure 5 is an enlarged perspective view of one
end portion of the fixture.

I claim:

The ornamental design for a fluorescent light-
ing fixture for passenger vehicles, as shown.

ERIC B. HALLMAN.
